UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

COUNTER AND SHANK FASTENING MACHINE.

Application filed January 2, 1919. Serial No. 269,284.

To all whom it may concern:

Be it known that I, JOSEPH H. POPE, a citizen of the United States, residing at Hamilton, in the county of Essex and State 5 of Massachusetts, have invented certain Improvements in Counter and Shank Fastening Machines, of which the following description, in connection with the accompanying drawings, is a specification, like 10 reference characters on the drawings indicating like parts in the several figures.

The present invention relates to nailing machines and is herein illustrated as embodied in a machine adapted to attach to a 15 molded counter a shape-retaining member, the finished product being designed for incorporation in a turn shoe in accordance with the process set forth in the patent to Thissell No. 1,302,994, May 6, 1919.

20 In accordance with the process disclosed in this patent a molded counter is incorporated in a shoe independently of the inseam which attaches the shoe upper to the sole, as distinguished from the alternative practice 25 in which the counter flange is included in the upper-attaching seam. Consequently it is essential to provide other suitable means in lieu of the inseam to insure the counter being so secured within the shoe as to retain 30 its shape and offer the support which it is intended to afford. The provision of such means is especially important for the forward ends of wings of the counter since they invariably extend beyond the heel breast line 35 of the shoe where it is impractical, especially in turn shoes, to fasten them securely to the sole because the fastenings would appear on the finished surface of the sole.

One manner of preparing the counter involves attaching to the inturned flange of 40 the counter a counter shape-retaining member in the form of a bottom piece for the counter termed a tuck, or utilizing the shank stiffener for this purpose.

45 It is an object of this invention to provide a machine organized to assemble accurately and efficiently a molded counter and a shape-retaining element for the counter in their final relative positions and permanently fasten them together preparatory to the incorporation of the counter in the shoe.

With this object in view, an important feature of the invention consists in a novel

organization of devices constructed and arranged to support a molded counter and a 55 shoe shank or other member adapted to preserve or retain the shape of the counter, means for locating the member in predetermined assembled relation to the counter, and mechanism operating permanently to 60 fasten the counter and member in their assembled relation. In the drawings a shank member is illustrated, the devices for supporting the counter and positioning the shank member being individually adjustable 65 and adjustable relatively to each other, and the mechanism for fastening the two together being arranged to insert simultaneously fastenings at either side of the counter at its forward ends and, if desired, to insert 70 additional fastenings in other portions of the counter. By the use of this organization, the counter and shank member may be quickly fastened together in a manner which insures the required shape of the counter 75 and the accurate location of the shank in the shoe and which enables the counter effectively to resist the strain to which it is subjected in the shoe.

As herein shown, the machine employs 80 headed nails to fasten the counter and the shank, automatically operating nail supplying mechanism being provided to deliver the nails in position to be inserted through the margin of the shank and the inturned flange 85 of the counter. Also, preferably, a clenching member, which also serves as a clamp between which and the counter supporting means the two parts are clamped, is provided to clamp the fastenings on the under 90 side of the counter.

A further feature of the invention consists in an improved organization or combination of nail supplying mechanism with a nail driving machine, with the end in view 95 of preventing the clogging of the nailing die or the nail transerrer by the delivery to either of those members of a second supply or load of nails before a previously delivered load has been removed therefrom. 100 This may be accomplished advantageously by a nail loader operative to deliver a single load of nails to the transerrer, after which it automatically ceases to operate until restored to operative condition by movement 105 of the transerrer to discharge the load of

nails which it has received. The loader is herein arranged so as to be actuated by the nail driving mechanism, with the consequent advantage that a load of nails is delivered 5 by the loader only when a previously delivered load is driven from the nailing die. It thus becomes impossible for two loads of nails to be in the nailing die at the same time. In a convenient construction the 10 loader is actuated by the nailing mechanism through connections which automatically become inoperative after a single actuation and which are restored to operative condition by the operator of the machine when 15 he moves the nail transerrer from receiving position with respect to the loader to delivery position with respect to the nailing mechanism. While this feature of the invention is herein illustrated and described 20 as embodied in a machine for nailing counters to shank pieces, it should be understood that it may be employed in the organization of other nailing machines.

Other objects and features of the invention will now be described in connection 25 with the accompanying drawings which illustrate a preferred embodiment of the invention and the invention will then be pointed out in the appended claims.

30 In the drawings,—

Fig. 1 is a front elevation of the upper part of a machine embodying a preferred form of the invention;

35 Fig. 2 is a perspective view of a counter prepared for incorporation in a shoe by the machine shown in Fig. 1;

Fig. 3 is a perspective view of the counter and shank supporting devices;

40 Fig. 4 is a view in horizontal section on the line 4—4 of Fig. 1;

Fig. 5 is a perspective view of the mechanism for controlling the delivery of nails to the nail loader;

45 Fig. 6 is a detail vertical section.

45 In the accompanying drawings the invention is shown as embodied in a machine of the type illustrated in Patent No. 446,885 granted Feb. 24, 1891 on an application of Joseph H. Pope to which reference may be had for a more complete description of the machine construction not herein described in detail.

50 The machine comprises a frame 2 provided with a stationary cross bar 4 in which 55 is formed a nailing die having a plurality of driver passages 6 through which reciprocate the drivers 8 carried by the reciprocating cross head 10. This cross head is secured to the upper ends of side rods 12 which reciprocate in vertical journals 14 formed in the frame 2. The reciprocation of the cross head 10 may be effected in a suitable manner as, for example, through a lower cross head connected to an eccentric on the driving 60 shaft of the machine as shown in the patent

to Pope above referred to. In the lower part of the frame 2, vertical guideways 16 are provided for a jack post 18 carrying a vertically adjustable anvil post 20 the top of which is formed as an anvil 22 heel-shaped 70 to engage the under side of a counter the jack post and anvil post being moved into work clamping position by means of a cam 23 suitably operated from the driving shaft of the machine. 75

Depending from the under side of the nailing die formed in the cross bar 4 is a block 28 which serves as the counter and tuck or shank supporting block while they are being fastened together. This block 28 80 is shaped to correspond to the inside of the counter and preferably to fit the smallest size of counter to be used so that it will not be necessary to substitute various sizes of these counter supporting blocks to accommodate the different sizes of counters. The bottom surface of the block is slightly convexed to correspond to the inside heel seat surface presented by the counter in the shoe. Driver guiding passages 6 are formed in 85 this block in continuation of the driver passages 6 in the nailing die. On opposite sides of the counter block 24 and near its forward end are a pair of counter holding clips 36 which extend downwardly and rearwardly 90 to a point near the lower edge of the counter, Fig. 3, and are curved to the contour of the sides of the counter so as to grip the counter and retain it on the block. These clips 36, which are conveniently narrow strips of 95 spring steel, depend from ears 37 carried by a left and right threaded screw 38 extending transversely through the forward upper portion of the block and having adjusting nuts 40 at either end. This screw 38 100 provides for simultaneous lateral adjustment of the clips 36 to hold the different sizes of counters on the block, the tuck or shank assembled with the counter determining the maximum to which the counter 110 wings may be pressed together and the spring clips hugging the outside of the counter so as to conform it to the shank and also centralizing it on the supporting block 28. Projecting forwardly and also downwardly from the cross bar 4 so as to engage the forward end of a shank, as shown in Fig. 3, is a shank positioning gage 42. The forward end 44 of this gage is forked to straddle the forward end of the shank and it is 115 mounted on the cross bar 4 for lateral adjustment by means of a slot and set nut 46. In assembling a counter and a shank it is very important to control the position in which the shank extends relatively to the 120 counter so that when incorporated in a shoe the counter will fit the heel end of the last and the shank extend forwardly in proper position between the inseam or ribs of the 125 shoe in the shank. This gage 42 by strad-

dling the forward end of the shank in the manner shown in Fig. 3 will accurately position the shank with respect to the counter and also hold it in such position during the 5 insertion of the fastenings. It will thus be seen that with the counter and tuck or shank supporting means illustrated it is possible to assemble the two members accurately and quickly in position to be fastened together.

10 Inasmuch as the counters for shoes invariably extend an appreciable distance beyond the heel breast line of the shoe it is essential to fasten the two together near the forward ends of the counter to prevent them 15 from spreading when incorporated in the shoe and accordingly the counter support, driver passages, drivers and anvil are all arranged to insert fastenings at the extreme forward ends of the counter flange as illustrated in Fig. 2.

A nail loader 48 is provided to furnish the nailing die with the required number of nails to be driven, these nails being preferably of the headed type to insure the holding 25 effect of the nails. This loader, which is substantially like that shown in the patent to Pope above referred to, briefly, comprises a frame 50 which is loosely mounted for rotation on the right hand side rod 12, 30 Fig. 1, above the stationary cross bar 4 and carries the heel shaped loader 48 having the nail passages 52. A shutter 54 which is slidably mounted on the under side of the nail loader serves to prevent the nails 35 from falling out during the transfer of the gang of nails by the loader to the nailing die, this shutter being operated in any well-known manner. To prevent the operation 40 of the drivers 8 while the loader is loading the nailing die the loader frame 50 is provided with a portion 56 which has a cam slot 58 adapted to engage a pin 60 on a horizontally slidable bar 62 which has connections with the clutch to prevent its operation, the slide being actuated by the engagement 45 of the cam slot with the pin 60 as the nail loader is brought into loading position.

The nail loader receives its supply of nails from a nail feeding mechanism mounted on 50 a shelf 66 attached to the frame 2 at one side of the machine. This nail feeding mechanism may conveniently be like that shown in Patent No. 1,129,882, dated Mar. 2, 1915, in the name of Ronald F. McFeely, 55 except that the illustrative mechanism is adapted to supply nine nails at one time to the loader 48. As herein shown, the nail feeding mechanism comprises a nail hopper 68 which operates to deposit the nails upon 60 a series of raceway grooves leading from the hopper and a separating slide 69 which is arranged to be reciprocated to discharge the nails into conductor tubes 71 which lead to the nail loading block 48. The hopper 68 65 is herein arranged so as to be oscillated dur-

ing each operation of the machine by connections with the reciprocating cross head 10 of the machine proper with the consequent advantage that a load of nails is delivered by the separator only when a previously delivered load is driven from the nailing die. It thus becomes impossible for two lots of nails to be in the nailing die at the same time. These connections comprise a vertically reciprocable rack bar 70 carried 70 on the upper end of a vertically disposed rod 72 held in bearings in the shelf 66. This rod 72 carries an adjustable collar 74 between which and a portion of the shelf 66 is a compression spring 76 encircling the rod 80 72. The adjustable collar 74 also carries a depending leg 78. Slidably mounted on the lower end of the rod 72 is a bracket 80 having a projecting pin 82 received in a slot 83 in one end of a lever 84 which is fulcrumed on a pivot bolt 86 having bearings in ears projecting from a portion of the shelf 66. The opposite end of this fulcrum lever 84 is connected by means of a link 88 to a collar 89 rigidly clamped on the 90 side rod 12 of the reciprocating cross head of the machine.

In order to prevent the clogging of the nailing die in the cross bar 4, or the nail loader or transferer 48 by the delivery to 95 either of those members of a second supply or load of nails before a previously delivered load has been delivered therefrom, a safety or non-repeating latch mechanism is provided. This safety mechanism is operative 100 to allow a single load of nails to be delivered to the nail loader after which it automatically ceases to operate until restored to operative condition by movement of the nail loader to discharge the load of nails 105 which it has received. Thus in the event that the cross head carrying the drivers is reciprocated a second time, as either accidentally or for the purpose of delivering a second blow to the nails, the nail feeding mechanism will fail to operate and a second load of nails will not be delivered to the nail loader 48. In the illustrated construction this mechanism is carried by the bracket 80 mounted on the rod 72 and consists of a switch plate 90 mounted for rotation in a horizontal plane about the rod 72. This switch plate 90 is provided with a hole 92 through which the leg 78 on the rod 72 may project and in the normal operative, position, the parts being shown in Fig. 5 in position to actuate the nail feeding mechanism, this hole is out of alignment with the leg 78. At one side of the switch plate 90 a lug 94 projects into the path of 110 one end of a push rod 96 which is mounted to reciprocate horizontally in bearings formed on the shelf 66. The other end of this rod is provided with a head portion 97 in position to be engaged by the opposed 115

(right hand) end of the slide 62 which is operated by the movement of the nail loader 48 into nail delivering position to prevent operation of the clutch while the nail loader 5 is in said position. Thus, as the nail loader 48 is transferred from nail receiving position under the tubes 71 to nail loading position over the nailing die, the end of the slide 62 engages the end of the rod 96 and 10 moves it lengthwise so that the other end of the rod, by engagement with the lug 94 on the switch plate 90, acts to rotate the switch plate a sufficient distance to bring the hole 92 out of alinement with the leg 78 on the 15 actuating rod for the nail feeding mechanism. A compression spring 98 encircling the push rod 96 and confined between one of the bearings for the rod and an adjustable collar on the rod serves to return the 20 rod into the normal inoperative position while a tension spring 100 fastened at one end to the bracket 80 and attached at its opposite end to an ear 102 formed on the switch plate tends to maintain the switch plate 25 with the hole 92 therein disposed in alinement with the leg 78. It will thus be seen that when the switch plate 90 is rotated to bring the hole 92 out of alinement with the leg 78, by reason of the movement of 30 the nail loader 48 into nail delivering position over the nailing die, the subsequent reciprocation of the driver carrying cross head 10 will, through the lever 84, raise the bracket 80; and the switch plate 90 consequently engages the leg 78 whereby the rod 72 will, through the rack bar 70, oscillate 35 the nail hopper 68.

For the purpose of locking the switch plate 90 in position for it to engage the 40 leg 78 and thus oscillate the nail hopper and as a result deliver a load of nails to the nail loader 48, the switch plate is further provided with a projecting lug 104 which is engaged by one end of a bell crank 45 lever 106 while the switch plate is in position to effect an operation of the nail supplying mechanism. The bell crank lever 106 is fulcrumed on the pin 108 on the bracket 80 and the end of the other arm 110 of the bell crank is engaged by a two-way switch 50 to effect a release of the switch plate 90 from the end of the arm 106 of the bell crank. This two-way switch device comprises a block 114 formed on the shelf 66 and 55 pivotally mounted on the front of the block on the bearing 116 is a wedge-shaped cam 118 the smaller upper portion of which carries a rearwardly projecting pin 120 received in a slot 122 formed in the block 114, this pin being acted upon by a spring 124 contained in a recess formed in the block at 60 substantially right angles to the rearwardly projecting pin of the cam. As the bracket 80 carrying the switch plate 90 is raised by 65 the lever 84 it carries the bell crank lever

106, 110 upwardly whereupon the end of the arm 110 travels up the outer or right-hand (Fig. 5) surface of the cam 118 which acts to rock the cam about its pivot 116 toward the left or against the compression of 70 the spring 124 thus maintaining the opposite arm 106 of the bell crank in engagement with the ear 104 and preventing it from being rotated into position to dispose the hole 92 beneath the leg 78 by reason of 75 its tension spring 100. As the bracket returns, however, to its inoperative position the bell crank is rocked by the action of the surface on the opposite side of the cam 118 on the arm 110 thus withdrawing the 80 arm 106 of the bell crank from engagement with the ear 104 on the switch plate 90. Thereby upon the return of the bracket to its normal inoperative position the tension spring 100 acts to rotate the switch plate 85 into position to dispose the hole 92 beneath the leg 78 and thereafter additional reciprocations of the driver carrying cross head 10 will not effect an operation of the nail feeding mechanism. A tension spring 126 secured to the arm 110 of the bell crank and to the shelf 66 tends normally to maintain the arm 106 in engagement with the periphery of the switch plate. 90

In the operation of the machine herein 95 illustrated a molded counter of the proper size and shape and having an inturned flange is first placed upon the counter supporting block 28, together with the shank piece or a tuck, the heel seat portion of this 100 member fitting within the counter and resting on the inturned flange as illustrated in Fig. 3. If the counter and shank piece are of the size for which the counter supporting block 28 was made they will fit snugly on 105 the block and be held in place by the side clips 36 which will have been adjusted so as to hug the sides of the counter. If the counter and shank piece are of a larger size, however, the side clips 36 are correspondingly adjusted by the set nuts 40 so that they will act to press the wings of the counter closely against the shank piece, the curvature of the side clips being such that they will hold the counter against the bottom and rear of the counter block 28. The forward end of the counter is then located within the prongs of the gage 42 whereby the direction of the shank relatively to the counter is accurately determined. With the counter accurately and positively held on the counter supporting block in this manner, the nail loader 48 is then swung by hand from the position shown in Figs. 1 and 4 into position over the nailing die, the shutter 54 of the nail loader being actuated to allow the nails to fall into the nailing die. The transfer of the nail loading device into this position causes the cam 58 on the frame 50 of the nail loader to engage the pin 60 130

on the slide 62 and move it longitudinally or to the right in Fig. 4. This movement of the slide causes the ear 94 on the switch plate 90 to be engaged by the rod 96 and the switch plate to be rotated into position to remove the hole 92 from under the leg 78 on the rod 72, thereby setting the non-repeating latch for the subsequent operation of the machine. The operator then starts the machine which first causes the jack post 18 to be moved in position for the counter and shank member to be clamped between the anvil plate 22 and the counter block 28. Thereafter the cross head 10 is lowered to drive the nails from the nailing die into the work, the ends or points of the nails being properly clenched on the underside of the counter by the anvil. Preferably nine nails are inserted in the counter and shank, the forward nails being located sufficiently near the forward ends or wings of the counter to insure against the wings being spread when the counter is incorporated in the shoe. By driving the fastenings in this manner the proper location of the nails in the flange of the counter and the margin of the shank is secured and inasmuch as the nails are all driven simultaneously while the two parts are held in accurately assembled relation, the proper location and maximum efficiency of the holding power of the nails is obtained. The reciprocation of the cross head 10 causes the lever 84 to be rocked about its fulcrum whereby the bracket 80 connected to the outer end of the lever is raised. By reason of the switch plate being positioned so as to abut against the end of the leg 78, as shown in Fig. 6, the rod 72 is raised against the action of the spring 76 to oscillate the nail hopper 68 and effect a delivery of nails by the separator 69 to the nail loader 48. During the reciprocation of the bracket with the rod 72 the arm 106 of the bell crank is held in engagement with the ear 104 on the switch plate so as to lock it in operative position against the tension of the spring 100. The locking of the switch plate by the arm 106 is not affected, of course, by the travel of the arm 110 on the right-hand surface of the cam 118 (Fig. 5) as the cam is rocked against the spring 124. Upon the return movement of the bracket 80 the arm 110 is forced, by reason of the opposed inclined surface of the cam, in an opposite direction. This serves to remove the arm from engagement with the ear 104 at which time the switch plate 90 is immediately returned by its spring 100 into position to prevent subsequent operation of the nail feeding mechanism. The oscillation of the nail hopper 68 effects the delivery of nails to the nail block preparatory to a second operation of the machine. Upon the return of the machine mechanism to its inoperative position, the counter and attached shank are removed

from the nail supporting block and a second counter and shank assembled and the operation repeated.

The invention has been described in connection with the attaching to a molded counter of a shank, one function of which is to cause the shape of the counter to be retained or preserved so that the forward ends of the counter may not be spread apart during the manufacture of the shoe in which it is subsequently incorporated. It should be understood, however, that the invention is not limited to the use of a shank as the shape-retaining or preserving member and that any suitable member adapted, when properly attached to the counter, to exercise this function may be employed.

Having thus described my invention, what I claim as new and desire to secure by Letters Patent of the United States is:

1. In a machine of the class described, the combination of relatively adjustable devices constructed and arranged to support a molded counter adjustably and hold the counter in predetermined shape, means for positioning a shoe shank in finally assembled relation to the counter, and mechanism constructed and arranged permanently to fasten the counter and the said shank in assembled relation.

2. In a machine of the class described, the combination of relatively adjustable devices constructed and arranged to support a molded counter adjustably and hold the counter in predetermined shape, means for positioning a shoe shank in finally assembled relation to the counter, and mechanism for inserting at a single operation a plurality of fastenings to attach a counter to the shank.

3. In a machine of the class described, the combination of relatively adjustable devices constructed and arranged to support a molded counter adjustably and hold the counter in predetermined shape, means for positioning a shoe shank in finally assembled relation to the counter, and mechanism constructed and arranged permanently to fasten the forward ends of the said counter to the said shank.

4. In a machine of the class described, the combination of devices organized for relative movement to support and hold successively differing counters in predetermined shape, means for holding a shoe shank in finally assembled relation to the counter, and mechanism operating permanently to attach the forward wings of the said counter to the said shank.

5. In a machine of the class described, the combination of devices constructed and arranged to support a molded shoe counter having an inturned flange and a shank disposed within the counter and resting upon its inturned flange, means operating to clamp the counter and the shank in as-

sembled relation, and mechanism for driving a gang of fastenings through the counter flange and a margin of the shank permanently to attach the counter and the shank.

5 6. In a machine of the class described, the combination of devices constructed and arranged to support a molded shoe counter and a shoe shank, means for locating the shank in predetermined assembled relation 10 to the counter, and mechanism operating permanently to attach the said counter and the said shank.

7. In a machine of the class described, the combination of devices constructed and arranged to support a molded shoe counter and a shoe shank, means for positioning and holding the forward end of the shank in finally assembled relation to the counter, means for clamping the counter and the shank in said 15 relation, and mechanism for inserting simultaneously a gang of fastenings to attach the counter to the shank.

8. In a machine of the class described, the combination of means for supporting a shoe 25 counter, including adjustable means to hold the counter in a predetermined shape, adjustable means for positioning a shoe shank in finally assembled relation to the counter, and mechanism constructed and arranged 30 permanently to fasten the said counter and the said shank in assembled position.

9. In a machine of the class described, the combination of a nailing die, an approximately counter shaped member projecting 35 from the die and adapted to support a flanged counter in predetermined shape and a shank, means adjustably carried by the counter support to position laterally the forward end of the shank relatively to the 40 counter, means for driving nails through said supporting member to attach the flange of the counter to the shank, and an anvil operating in opposition to the driving means for clinching the nails.

45 10. In a machine of the class described, the combination of devices constructed and arranged to support a counter and a tuck for the counter in assembled relation to each other, mechanism for inserting fastenings to attach the counter and the tuck, nail feeding mechanism actuated by said fastening inserting mechanism and a nail loader movable from nail receiving position with respect to the nail feeding mechanism to nail delivering position with respect to the fastening inserting mechanism.

11. In a machine of the class described, the combination of devices constructed and arranged to support a counter and a tuck 60 for the counter in assembled relation to each other, mechanism for inserting fastenings to attach the counter and the tuck, nail feeding mechanism, connections between said inserting mechanism and the nail feeding mechanism constructed and arranged 65 to effect another operation of the feeding mechanism.

to effect a single operation of the nail feeding mechanism from the inserting mechanism, and a nail loader movable from nail receiving position with respect to the nail feeding mechanism to nail delivering position with respect to the nail inserting mechanism. 70

12. In a machine of the class described, the combination of means shaped to enter and support a flanged counter and a tuck 75 for the counter, mechanism operating through the counter supporting means for inserting fastenings to secure the flange of the counter to the tuck, a loader for delivering fastenings into position to be inserted 80 by said fastening inserting mechanism, and a fastening feeding mechanism actuated by said fastening inserting mechanism to supply fastenings to the loader.

13. In a machine of the class described, the combination of nail driving mechanism, nail feeding mechanism actuated by said nail driving mechanism, and a nail loader movable from nail receiving position with respect to the feeding mechanism to nail delivering position with respect to the nail driving mechanism. 85 90

14. In a machine of the class described, the combination of nail driving mechanism, nail feeding mechanism actuated by said nail driving mechanism, a nail loader movable from nail receiving position with respect to the feeding mechanism to nail delivering position with respect to the nail driving mechanism, and means under the control of the 95 loader for controlling the operation of the nail feeding mechanism.

15. In a machine of the class described, the combination of nail driving mechanism, nail feeding mechanism actuated by said nail driving mechanism, a nail loader movable from nail receiving position with respect to the feeding mechanism to nail delivering position with respect to the nail driving mechanism, and means under the control of the 105 loader for controlling the delivery of nails from the feeding mechanism to the loader. 110

16. In a machine of the class described, the combination of nail driving mechanism, nail feeding mechanism, connections between 115 said nail driving mechanism and the feeding mechanism constructed and arranged to effect a single operation of the feeding mechanism from the driving mechanism regardless of the number of operations of the latter, and means for readjusting said connections to effect another operation of the feeding mechanism. 120

17. In a machine of the class described, the combination of nail driving mechanism, nail feeding mechanism, connections between 125 said mechanisms constructed and arranged to effect a single operation of the feeding mechanism from the driving mechanism regardless of the number of operations 130

- of the latter, and means under the control of the operator for re-adjusting said connections to effect another operation of the feeding mechanism.
- 5 18. In a machine of the class described, the combination of nail driving mechanism, nail feeding mechanism, a nail loader, connections between said mechanisms constructed and arranged to effect a single operation of the feeding mechanism from the driving mechanism regardless of the number of operations of the latter, and means under the control of the loader for readjusting said connections to effect another operation of the feeding mechanism. 70
- 10 19. In a machine of the class described, the combination of nail driving mechanism, nail feeding mechanism, a nail loader movable from nail receiving position with respect to the feeding mechanism to nail delivering position with respect to the driving mechanism, non-repeating connections between said mechanisms constructed and arranged to effect a single operation of the feeding mechanism when the driving mechanism is operated, and means operated by movement of the loader from nail receiving to nail delivering position for readjusting said connections to effect another operation of the feeding mechanism. 80
- 15 20. In a machine of the class described, the combination of nail driving mechanism, nail feeding mechanism, a nail loader movable from nail receiving position with respect to the feeding mechanism to nail delivering position with respect to the driving mechanism, power transmitting connections between said mechanisms constructed and arranged to become inoperative after a single operation, and means under the control of the loader for restoring said connections to operative condition. 85
- 25 21. In a machine of the class described, the combination of nail driving mechanism, nail feeding mechanism, a nail loader movable from a nail receiving position with respect to the feeding mechanism to nail delivering position with respect to said driving mechanism, and means for delivering nails from the feeding mechanism to the loader controlled by operation of the driving mechanism and the loader. 90
- 30 22. In a machine of the class described, the combination of a nail driving mechanism, nail feeding mechanism, a nail loader movable from nail receiving position with respect to the feeding mechanism to nail delivering position with respect to said driving mechanism, driving connections between said mechanisms, automatically rendered inoperative by a single actuation, and means under the control of the operator for restoring said connections to operative condition. 95
- 35 23. In a machine of the class described, the combination of nail driving mechanism, nail assorting and feeding mechanism actuated by said nail driving mechanism, connections between said mechanisms, means for rendering said connections inoperative and means for restoring said connections to operative condition. 100
- 40 24. In a machine of the class described, the combination of nail driving mechanism, nail assorting and feeding mechanism actuated by said nail driving mechanism, connections between said mechanisms, automatic means for rendering said connections inoperative, and means for restoring said connections to operative condition. 105
- 45 25. In a machine of the class described, the combination of nail driving mechanism, nail assorting and feeding mechanism actuated by said nail driving mechanism, connections between said mechanisms, automatic means for rendering said connections inoperative, and manually controlled means for restoring said connections to operative condition. 110
- 50 26. In a machine of the class described, the combination of nail driving mechanism, nail feeding mechanism arranged in cooperative relation to said driving mechanism actuating means for the feeding mechanism including relatively movable power transmitting elements and an interponent movable into and out of position to prevent relative movement of said elements. 115
- 55 27. In a machine of the class described, the combination of nail driving mechanism, nail feeding mechanism, power transmitting connections between said mechanisms, said connections including elements capable of relative movement to render them inoperative to transmit power, a movable interponent, and means for inserting the interponent between said relatively movable elements to cause power to be transmitted to the feeding mechanism. 120
- 60 28. In a machine of the class described, the combination of means for supporting a molded counter with its forward ends spaced apart a predetermined distance, means for holding a rigid member of sheet material upon the inturned flange of the counter, and means for driving a plurality of fasteners through the member and flange. 125
- 65 29. In a machine of the class described, the combination of relatively adjustable devices constructed and arranged to support a molded counter adjustably and hold the counter in predetermined shape, means for positioning a shape-retaining member in finally assembled relation to the counter, and mechanism constructed and arranged permanently to fasten the counter and the said shape-retaining member in assembled relation. 130
- 70 30. In a machine of the class described, the combination of relatively adjustable devices constructed and arranged to support

a molded counter adjustably and hold the counter in predetermined shape, means for positioning a shape-retaining member in finally assembled relation to the counter, 5 and mechanism for inserting at a single operation a plurality of fastenings to attach the counter to the shape-retaining member.

31. In a machine of the class described, 10 the combination of relatively adjustable devices constructed and arranged to support a molded counter adjustably and hold the counter in predetermined shape, means for positioning a shape-retaining member in finally assembled relation to the counter, 15 and mechanism constructed and arranged permanently to fasten the forward ends of the said counter to the said shape-retaining member.

32. In a machine of the class described, 20 the combination of devices organized for relative movement to support and hold successively differing counters in predetermined shape, means for holding a shape-retaining member in finally assembled relation to the counter, and mechanism operating permanently 25 to attach the forward wings of the said counter and said shape-retaining member.

33. In a machine of the class described, 30 the combination of devices constructed and arranged to support a molded shoe counter having an inturned flange and a shape-retaining member disposed within the counter and resting upon its inturned flange, means 35 operating to clamp the counter and the shape-retaining member in assembled relation, and mechanism for driving a gang of fastenings through the counter flange and

the margin of the shape-retaining member permanently to attach the counter and the 40 shape-retaining member.

34. In a machine of the class described, 45 the combination of devices constructed and arranged to support a molded shoe counter and a shape-retaining member, means for locating the shape-retaining member in predetermined assembled relation to the counter, and mechanism operating permanently 50 to attach the said counter and the said shape-retaining member.

35. In a machine of the class described, 55 the combination of devices constructed and arranged to support a molded shoe counter and a shape-retaining member, means for positioning and holding the forward end of the shape-retaining member in finally assembled relation to the counter, means for clamping the counter and the shape-retaining member in said relation, and mechanism for inserting simultaneously a gang of 60 fastenings to attach the counter to the shape-retaining member.

36. In a machine of the class described, 65 the combination of means for supporting a shoe counter, including adjustable means to hold the counter in a predetermined shape, adjustable means for positioning a shape-retaining member in finally assembled 70 relation to the counter, and mechanism constructed and arranged permanently to fasten the said counter and the said shape-retaining member in assembled position.

In testimony whereof I have signed my name to this specification.

JOSEPH H. POPE.
